UNITED STATES PATENT OFFICE.

JOHN G. KOENEN, OF MOUNT VERNON, NEW YORK.

DESIGN FOR AN EYEGLASS-CASE.

SPECIFICATION forming part of Design No. 29,485, dated October 18, 1898.

Application filed September 8, 1898. Serial No. 690,535. Term of patent 14 years.

To all whom it may concern:

Be it known that I, JOHN G. KOENEN, a citizen of the United States, and a resident of Mount Vernon, in the county of Westchester and State of New York, have invented and produced a new and original Design for Eye-glass-Cases, of which the following is a specification.

In the accompanying drawings, to which reference is made and which form a part of this specification, Figure 1 is a perspective view of my newly-designed eyeglass-case partially open, and Fig. 2 is a plan view of the same closed.

5 A A represent slightly curved or dished surfaces of the cover of the eyeglass-case. From a point near the edge B of the cover and at the center thereof the same is bulged at C and given a steeper slope than that of

the curved or dished surfaces A A, and this elevated surface C joins the curved surfaces A A by sloping sides D D. The edge E of the eyeglass-case is shaped with an outward bend or curve F at the center thereof, and from this curved portion the front slopes downward to the bottom of the case, the sides H H thereof sloping down to the slightly dished or curved surfaces J J of the front.

Having thus described my invention, what I claim as new, and desire to secure by Letters Patent, is—

The design for an eyeglass-case as herein shown and described.

JOHN G. KOENEN.

Witnesses:

H. A. WEST,
A. D. GREENFIELD.
